[57] CLAIM

The ornamental design for a table frame, substantially as shown and described.

DESCRIPTION

FIG. 1 is a perspective view of a table frame showing my design;

FIG. 2 is a top plan view;

FIG. 3 is a side elevational view, the opposite side being a mirror image thereof; and

FIG. 4 is a side elevational view thereof taken 45 degrees from the view of FIG. 3.

The table top disclosed by means of broken lines is shown for illustrative purposes only.

FIG. 1

FIG. 2

FIG. 3

FIG. 4
